DESIGN FOR A WHEELED TOY.

SPECIFICATION forming part of Design No. 22,863, dated October 31, 1893.

Application filed September 7, 1893. Serial No. 485,020. Term of patent 3½ years.

To all whom it may concern:

Be it known that I, CHARLES A. BAILEY, a citizen of the United States, and a resident of Cromwell, in the county of Middlesex and State of Connecticut, have invented a new and useful Design for Wheeled Toys; and I do declare the following to be a full, clear, and exact description of the invention, such as will enable others skilled in the art to which it appertains to make and use the same, reference being had to the accompanying drawing, and to letters of reference marked thereon, which forms a part of this specification.

15 The figure is a representation of the invention.

This invention has relation to a certain new and original design for a wheeled toy, and it consists in the novel form and configuration 20 of parts, as hereinafter described.

The principal feature of the design consists in a body portion having the form or representation of a galley, or boat, a representation of a standing figure in the bow portion of said

body, and seated figures or representations of 25 rowers behind said standing figure or representation.

Referring to the accompanying drawing illustrating the design, the letter A indicates the body portion, having the form or representation of a galley or boat, mounted upon wheels, and having an overhanging stern portion, B and a figure head C at the bow. Standing in the bow portion is an erect figure or representation D of a man, carrying a flag E. 35 Seated behind said standing figure or representation, are figures or representations F of rowers, two upon each side.

What I claim is—

The design for a wheeled toy, substantially 40 as herein shown and described.

In testimony whereof I affix my signature in presence of two witnesses.

CHAS. A. BAILEY.
